CLAIM

The ornamental design for a display screen with a graphical user interface, as shown and described.

DESCRIPTION

A portion of the disclosure of this patent document contains material to which a claim for copyright is made. The copyright owner(s) has no objection to the facsimile reproduction by anyone of the patent document or the patent disclosure, as it appears in the Patent and Trademark Office patent file or records, but reserves all other copyright rights whatsoever.

The FIGURE is a front view of a display screen with a graphical user interface.

The electronic device shown in broken lines illustrates environmental subject matter, whereas the broken lines showing a display screen and elements of the graphical user interface illustrates portions of the article. The broken lines form no part of the claimed design.
